CLAIM

The ornamental design for pedicure slippers, as shown and described.

DESCRIPTION

FIG. 1 is a top perspective view of a right foot pedicure slipper, in assembled use position showing my design;

FIG. 2 is a top plan view of the slipper shown in FIG. 1 but as a flat non-assembled blank;

FIG. 3 is a bottom plan view of FIG. 2;

FIG. 4 is a left side view of FIG. 2;

FIG. 5 is a right side view of FIG. 2;

FIG. 6 is a rear elevational view of FIG. 2;

FIG. 7 is a front elevational view of FIG. 2;

FIG. 8 is a top perspective view similar to FIG. 1 but showing a left foot slipper in assembled use position;

FIG. 9 is a top plan view of the slipper shown in FIG. 8, but as a flat non-assembled blank;

FIG. 10 is a bottom plan view of FIG. 9;

FIG. 11 is a left side view of FIG. 9;

FIG. 12 is a right side view of FIG. 9;

FIG. 13 is a rear elevational view of FIG. 9; and,

FIG. 14 is a front elevational view of FIG. 9.

The dotted line representations of loop and pile connecting patches shown in FIGS. 2, 3, 9 and 10 are to illustrate environment only and form no part of the claimed design.
